MULTIPLE PUMP

Louis Beeh, Long Meadow, Mass.

Application July 4, 1944, Serial No. 543,445

9 Claims. (Cl. 103—6)

The invention relates to a multiple pump for two media, such as the fuel and lubrication oil of internal combustion engines, and it contemplates the provision of a pump of that kind which is particularly well suited for use, e. g. as an injection pump for engines of the constant pressure type with spark ignition. The invention also aims to provide a combined fuel and oil pump of relatively simple structure wherein the pressure oil delivered may be utilized, on the one hand, to lubricate the movable parts of the pump and, if so desired, also of extraneous devices, and on the other hand, to serve as a working medium in a device controlling the injection of fuel delivered by the pump to a cylinder or a plurality of cylinders of an engine to which the pump may be connected. According to the further invention, such controlling device may be rendered responsive to the vacuum prevailing in the manifold of such engine in order to adjust the quantity of fuel delivered to the engine cylinders.

The invention mainly consists in the combination of a pump of the rotary vane type with a plunger pump of the reciprocating type wherein a spring-biased plunger is shiftable in a radial cylindrical chamber of the rotor and both the fluid-propelling elements, i. e. the vane-like element and the plunger engage each other so as to mutually cooperate, the one in transmitting driving motion to the other. In the preferred form for use with multiple cylinder engines both the rotary pump and the reciprocating plunger pump parts comprise a plurality of fluid propelling members, that means there are a plurality of plungers operating in as many cylindrical chambers respectively of the rotor to pump fuel and there are also as many vane-like members operating in one stationary pump eccentrically arranged in relation to the rotor chamber or operating in a plurality of such chambers one after the other in order to pump oil, wherein, however, the number of pump chambers of the one kind need not be the same as that of the other kind. In a modified form of the invention, the pump part comprising the reciprocating plungers may be used as the oil pump, whereas the part comprising the vane-like elements may constitute the fuel pump. Further, according to the invention the delivery of the pumped fuel occurs from a pressure chamber through a plurality of ports, as many as there are cylinders of the engine to be charged by the pump, and these ports are controlled by a piston-like valve rotat-

sure difference of the fuel and oil in order to meter the quantity of fuel ejected through the ports. The invention also consists of means whereby the valve may respond to changes in the vacuum prevailing in the manifold of a machine to which the pump is attached. Other means may be provided in order to utilize the pumped oil for lubricating movable parts of the pump and/or extraneous parts, and also means to prevent the fuel pressure and the oil pressure from rising beyond a predetermined maximum.

Further objects and details of the invention will be apparent from the description given hereinafter and the accompanying drawings illustrating embodiments thereof by way of example.

In the drawings,

Fig. 1 is a longitudinal cross-section of a pump according to the invention, along line 1—1 of Fig. 2;

Figs. 2 to 6 are transverse cross-sections along lines 2—2 to 6—6 respectively of Fig. 1;

Figs. 7 to 9 are cross-sections along the radii 7 to 9 respectively of Fig. 2, wherein in each case one of the rotor plungers is shown having its axis coincident with the plane of the cross-section;

Fig. 10 is a longitudinal cross-section of another embodiment; and

Fig. 11 is a diagrammatical, longitudinal cross-section of a portion of another embodiment for use as a two-stage pump for only one medium.

Referring now to the drawings, the embodiment of Figs. 1 to 9 comprises a housing 11 consisting mainly of three coaxial parts 12, 13, 14 held together by means such as screw bolts 15 and 16 respectively. Parts 12 and 13 enclose a cylindrical space 17 formed by a disc-like portion 18 of part 13 and a disc-like portion 19 and a ring-shaped wall 20 of part 12. This space is lined by a lower plate 21, an upper plate 22 and a ring 23, the plates and the ring being secured by the aforementioned bolts 15 against any movement in relation to the housing. Internally of the members 21 to 23 a disc-shaped rotor 24 is rotatable, the lower shaft portion 25 of which is journaled in a sleeve-like portion 26 of the housing and projects therefrom so that it may be connected with an extraneous driving element (not shown) for rotation, whereas the upper shaft end 27 of the rotor has its bearing in a tubular extension 28 of the plate 22. The ring 23 is internally so shaped as to form together with the rotor 24 and the plates 21 and 22, the chamber or plurality of chambers of the rotary pump part of the device. As stated hereinbefore,

the number of said chambers may be selected according to the requirements in each case. In the present embodiment two such chambers 29 and 30 are provided by eccentric portions of the ring 23 as best seen in Fig. 3.

Rotor 24 is provided with a number—in the present embodiment five—of cylindrical chambers 31 which open towards the inner face of ring 23. Interiorly of each chamber 31 a plunger 32 is movable, which is peripherally recessed at 33 for a purpose to be explained hereinafter. Plunger 32 is biased by a spring 34 between the bottom of its cylinder chamber 31 and the plunger 32. In Fig. 3, a plunger 32 with spring 34 is shown in only one of the chambers 31 in order to avoid overcrowding of the figure, and to show more clearly certain ports in the cylinders which will be described hereinafter. Vane-like elements are provided in order to propel fluid through the chambers 29 and 30 when the rotor rotates. I have found that particularly good results can be obtained if these elements are in the form of rollers. Such rollers 35 are interpositioned between the inner wall of ring 23 and the upper ends of the plungers 32 so that each associated spring 34 tends to urge the roller against ring 23. On the other hand, if the rotor rotates, the inner wall of ring 23 will urge a roller approaching the narrow portion of the ring space towards the rotor axis, thereby pushing the plunger 32 in the same direction against the restraint of the spring 34. In order to make such movement of the roller possible, the side wall of the rotor is provided with slots 36 which serve to guide the rollers in radial direction with respect to the rotor.

Inlet ports and outlet ports are provided in the various chambers and conduits are provided in order to convey fluid to and from the rotary pump part as well as to and from the plunger pump part. In the embodiment of Figs. 1 to 9 fuel is to be delivered by the plunger pump part, whereas the rotary pump part is used to deliver oil for lubricating purposes of the various movable members of the device and also for the purpose of controlling the delivery of fuel to an extraneous machine. For this purpose the housing has a lateral inlet socket 37 which communicates with a conduit having a vertical branch 38 and two substantially horizontal branches 39 which extend to arcuate slots 40 provided in plate 21. Slots 40 are arranged on the same radius as two cross bores 41 and 42 in each of the cylinders 31. Similar arcuate slots 43 are provided in the upper plate 22 but on diameters at right angles to those of the slots 40. The relative location of the slots 40 and 43 will be apparent from a comparison of Figs. 2 and 4. Slots 43 are in communication with an annular space 44 formed between the housing part 13 and the tubular extension 28 of the plate 22. Now it will be clear that fuel entering from the socket 37 will fill the conduits 39 and slots 40 to enter the bore 41 of each cylinder 31 which during the rotation of rotor 24 happens to be in a position in which the bore 41 registers with a slot 40. On the other hand, when a chamber 31 is in a position in which its bore 42 registers with one of the slots 43 fuel may be expelled from that chamber 31 into the ring space 44. Ring space 44 opens into cylinder chamber 45 in which a plunger-like slide valve 46 is movable in axial and peripheral directions. The slide valve has a tapering groove 47 in its side wall to control by its movement a plurality of outlet ports 48 provided in the wall of the hous-

ing part 13, so that fuel from the space 44 and chamber 45 can be discharged through the outlet ports 48 in accordance with a movement of the valve 46. Preferably there are as many outlet ports 48 as there are cylinders in the engine to be charged by the pump. Each outlet port may also be equipped with a check valve 49 as clearly shown in Fig. 1. The number of outlet ports 48 may differ from that of the pump chambers 31 in the rotor. However, the fuel pump parts should be so dimensioned that they discharge into space 44, per each rotor revolution, a quantity of fuel not less than the maximum total which may be required to be discharged through the ports 48.

15 In order to prevent the occurrence of excessive pressure a relief valve 50 may be located in the housing part 13 so as to connect space 44 with inlet conduit 38 through openings 51 and 52 of the valve chamber 53 when the valve member or ball 54 is raised from its seat against the restraint of spring 55.

Another socket 56 is in communication with an arcuate conduit 57 in the housing part 12 and ending in two diametrically opposite slots 58 of disc plate 21 underneath the crescent-shaped chambers 29 and 30 respectively of the rotary pump part, as shown in Figs. 2 and 3. Angularly spaced from the slots 58 are outlet slots 59 in the upper plate 22 (Fig. 4). The slots 59 communicate each with a conduit 60 (Figs. 1 and 9) extending to the top of chamber 45 so as to fill that chamber on top of the plunger valve 46 except for the space taken by an additional member to be described hereinafter. From the foregoing it will be clear that upon rotation of the rotor taking along the rollers 35, oil may be sucked through the inlet 56 and slots 58 into the pump chambers 29 and 30 to be pressed out through slots 59 and conduits 60 thereby filling 40 the upper portion of chamber 45 and subjecting the plunger valve to the pressure difference of the oil on top and the fuel beneath it. In addition to groove 47, a helical groove 61 is provided on the outer wall of the plunger 46 and in communication with the upper part of chamber 45 through an opening 62. The lower end of the groove 61 ends in a radial bore 63 which communicates with a central bore 64 of a lower extension 65 of the plunger and in continuation thereof with an axial bore 66 of the rotor shaft 25. By means of a radial bore 67, a groove 68 longitudinally of the shaft 25 and a cross bore 69 in the housing, oil from the upper portion of chamber 45 may reach a relief valve 70 in the housing part 12 in order to return oil to the inlet conduit 57 when the oil pressure reaches a predetermined height. It will be clear that the groove 68 may serve not only as a conduit to the last mentioned valve, but also to lubricate the lower bearing of the shaft in the housing portion 26. Similarly, branch grooves 71 and 72 in connection with the bores 64 and 66 may be provided for the upper bearing of the rotor shaft and for the extension 65 of plunger 46 which is in a splined connection with the rotor shaft as will be explained hereinafter. Other oil grooves may be provided to lubricate the contacting surfaces of the rotor 24 and the plates 21 and 22. For this purpose, plate 21 has on its upper side a plurality of arcuate grooves 74 each with a radial branch 75 extending to the periphery of the plate so as to communicate with the pump chambers 29 and 30 respectively. Similar oil grooves 76 with radial branches 77 may be worked 70 in the lower side of the plate 22. Cross bores

18 are provided in the rotor through the cylinders 31 in such a position that they may register with the arcuate slots 74 and 76 and the radius of these slots and the location of the bores 78 are such that oil may enter into the annular space formed by the recessed portions 33 of the piston 32 in the chambers 31. It has been stated hereinbefore that the relief valve 10 will open under a certain pressure. This pressure will be so selected that correct functioning of the plunger valve 46 will be insured while oil may circulate from the rotary pump part through the upper portion of chamber 45 and back again to the oil inlet conduit 57 through the connecting conduits and valve 70. Inasmuch as, however, there is a possibility of a dangerous super-pressure occurring, another relief valve 79 may be provided and set to open at a higher pressure than valve 10 so as to act as a safety valve. Valve 79 is located in the interior of the rotor shaft 25 so that the oil pressure in conduit 66 bears thereon against the restraint of a spring 80 which is carried by a nut 81 screwed into the shaft 25 and which has an axial bore 82 through which valved oil can escape to the outside.

It has been stated hereinbefore that plunger valve 46 is in a splined connection with the upper portion 27 of the rotor shaft. In fact, as clearly apparent from Fig. 5, the plunger extension 65 has a square cross-section and engages a correspondingly shaped axial bore 83 of the shaft. In consequence, plunger 46 will rotate together with the rotor and thereby connect the outlet ports 48 one after the other with the fuel-filled chamber portion 45 in timed relation to the rotor rotation. The quantity of fuel ejected through each outlet 48 during one revolution depends upon the size of the cross-section of the groove 47 which at the time of its passage is in registry with the outlet port. This depends in turn upon the position of the plunger 46 in the axial direction of the chamber 45 and therefore, also on the pressure difference of the fuel and the oil in the opposite portions of the chamber. In addition thereto and according to the invention, the plunger position is rendered dependent on the pressure prevailing in the manifold of the engine to which the pump is applied. For this purpose the top portion 14 of the housing has an axial threaded bore 85 for connection to such manifold. Bore 85 opens into the interior of a bellows 86 secured to the lower side of portion 14 and the lower end of the bellows is secured to a plate 87 interiorly of the hollow portion of the cup-shaped plunger 46. Interiorly of the bellows a compression spring 88 is positioned between plate 87 and the housing top 14, tending to urge plate 87 downward. An anti-friction bearing such as a ball 89 is positioned between plate 87 and the bottom of plunger 46 so that the latter may rotate in relation to the bellows without subjecting it to torsional stress. Now it will be clear that the position of the plunger 46 in chamber 45 depends on the one hand on the pressure difference between the fuel and oil in chamber 45 as hereinbefore stated. On the other hand, there acts upon the plunger the pressure of the spring minus the oil pressure on plate 87 and the vacuum of the manifold. Thus, by properly selecting the forces of the spring of the relief valves 50 and 70 and of the spring 88, and properly dimensioning the cross-section of the groove 47, a system can be attained in which the plunger position in chamber 45 is such that desired quantities of fuel will be deliv-

ered in accordance to the vacuum prevailing in the manifold of an engine.

In order to apply the pump according to the invention to an engine, the following connections are to be made: sockets 37 to a fuel source; ports 48 with check valves 49 to the fuel inlet nozzles of the engine cylinders; the port 85 in the housing cover 14 to the manifold of the engine; shaft 25 to a part of the engine rotating with half the engine crank shaft revolutions, in the case of a four-stroke cycle; and if the oil pump part is to be used to lubricate parts of the engine, a connection may be also established between the lateral opening of the conduit 60 which otherwise will be closed by means of a plug 90. According to the relative arrangements of the inlet ports 58 and the outlet ports 59 in relation to each other, the illustrated pump should turn in counterclockwise direction, indicated by the arrow *a* in Fig. 2.

The pump will then operate as hereinafter described: Considering one of the rotor cylinders 31, in a position in which its axis coincides with the radius 7 in Figs. 2 to 4, the relative position of the parts will then be that as shown in Fig. 7. In this figure, the cross-section of the pump chamber 30 covered by the pertaining roller 35 is very narrow and the roller proper is almost at the bottom of its slot 36 in rotor 24. The associated plunger 32 is almost in its farthest backward position in which, however, there is communication between the slot 40 in the lower plate 21 and the lower portion of bore 41, so that fuel may enter into the chamber 31 from the inlet conduit 39. The upper portion of bore 41, however, is covered by the upper plate 22. The recess 33 of the plunger is just in front of the holes 78 so that oil present in the slots 74 of the lower plate and slots 76 of the upper plate will get to the surface of the front portion of plunger 32. The space of the chamber 30 will just begin to be connected to the oil inlet 58 (Fig. 2) because the roller preceding the one just contemplated will have advanced far enough so that the oil from port 58 may enter behind it. While the contemplated cylinder moves on during the rotation of the rotor, the oil in the chamber 30 between the roller of the contemplated cylinder and the one forward of it will be propelled forward, some of it passing into the slots 74 and 76 through their radial branches 75 and 77 respectively. When the axis of the contemplated cylinder coincides with the radius 8, the parts are in the position shown in Fig. 8 in which the oil inlet 58 is covered by the roller 35. Lubrication connection, however, exists between the plunger recess 33 and the lubricating grooves 74 and 76. In the meantime, the lower port 41 of the plunger chamber has been closed by the plate 21, whereas the upper portion of the bore 41 is in connection with the annular space 44 through the slot 43 of the plate 22. It will be clear that on the way from the position 7 to 8 until the contemplated chamber 31 reaches the position of the topmost one in Fig. 3, the spring 34 via the plunger 32 forces the roller 35 outside to contact the ring 23. From there on, through the next 90° of rotation, the roller will force the associated plunger backward against the restraint of the spring 34 owing to the eccentric shape of the ring 23. From the position in registry with radius 8 to and even beyond that of Fig. 9, the roller 35 will propel oil from the chamber 30 through the slot 59 (Fig. 9) into the pressure of conduit 60. Simultaneously, the

plunger being shifted inward in chamber 31 will have reduced the volume of the latter and in view of the existing connection between the upper part of the bore 41 with the slot 43 in the top plate 22, while the lower portion of the bore 41 is closed by plate 21, fuel will be expelled into the annular space 44. A similar operation takes place in the other semi-circle owing to the presence of two symmetrically arranged pump chambers 30 and 29. Furthermore, since there are shown five cylindrical chambers 31 with plungers 32 and rollers 33 each cycle, i. e. one complete revolution of the rotor, includes the delivery of ten equal part quantities of fuel to the annular space 44 and also the delivery of ten part quantities of lubrication oil to the conduit 60.

While the rotor rotates in the indicated manner, it takes along the plunger valve 46 as hereinbefore described. Thereby the tapered slot 47 passes the fuel discharge ports 48 one after the other and permits a quantity of fuel under the pressure of the pump to escape through the ports and connected check valves 49 to charge the cylinders of the engine. The quantity of the fuel passing in each instant through a port 48 will depend on the one hand on the pressure prevailing in the annular space 44 and the lower portion of the chamber 45. If this pressure exceeds a predetermined maximum, relief valve 54 will open to permit some fuel to escape through the port 51 and to flow back to the fuel inlet conduit 38. The quantity of fuel discharged through port 48 is further dependent on the size of the cross-section of the groove 47 passing the port 48 or in other words, it will be dependent on the axial position of the plunger 46. As hereinbefore described, the latter is exposed to the pressure of the fuel in chamber 45 on the one hand and on the other hand to the oil pressure in the upper portion of chamber 45 which is charged with the oil pumped through the conduit 60. Furthermore, the plunger is loaded by spring 88 against the force of which a vacuum within the bellows 86 is acting owing to its connection to the manifold. Thus when the pump is operating uniformly the position of the plunger will essentially depend on the existing vacuum in the manifold, that means the lower the vacuum the higher will be the position of the plunger, so that more fuel will be discharged to the ports 48 if the vacuum becomes lower and that the quantity of fuel decreases when there is less vacuum prevailing within the bellows 86.

While thus fuel is discharged, lubricating oil pumped into the upper portion of chamber 45 passes through the helical groove 61 in the plunger surface. It will be noticed that during rotation of the plunger 46 the helical groove 61 will register with one of the ports 48 after the other, similar to the groove 47 though at different times. However, there is no danger of oil passing through the valves 49 because the latter will be set to open according to the required fuel pressure which for injection purpose generally is of a magnitude of 1000 or 1500 lbs. whereas the oil pressure in the groove 61 might be in the neighborhood of say 40 or 60 lbs. only. From groove 61, the oil flows on through the conduits 63, 64, 66, 67, 69 to the relief or circulating valve 70 to return to the oil inlet conduit 57. The mentioned branch grooves such as 71, 72 and the lower portion of the grooves 68 serve to lubricate the bearings of the rotating shaft 25 and the sliding surfaces between that shaft and the plunger ex-

tension 65. If the pressure in the oil system exceeds a predetermined maximum, oil may escape through relief valve 79 and the bore 82.

In the device just described, fuel is pumped by a plurality of plungers operated in cylinders provided in a rotor, whereas lubricating oil is pumped by rollers operating in the manner of vanes in a rotary pump comprising mainly the said rotor with said rollers operating in an eccentric chamber. Now it will be clear that with certain modifications, it is also possible to use the rotary pump part to deliver fuel and the plunger pump part provided in the rotor to pump lubricating oil. Further, the structure and arrangement of parts may be modified by which an automatic adjustment of the control plunger position under the action of a vacuum in a manifold is attained. An example of such modifications is illustrated in the embodiment of Fig. 10. In this embodiment the housing comprises the parts 101, 102, 103 and 104 connected to each other by screw bolts some of which are indicated at 105 and 106. A rotor 107 is arranged in the lower housing portion 101 in a manner similar to that of Fig. 1 and the housing is provided with plates 108 and 109 between which the rotor is rotatable. There is further a ring 110 to form eccentric pump chambers 111 with the rotors, and a conduit 112 permits fuel from the inlet 113 to enter chamber 111 through a slot 114. Fuel may be discharged from this chamber 111 through a slot or slots 115 in the upper plate 109 of the annular chamber 116 which is similar to the chamber 44 in the embodiment first described. The openings 114 are under the control of rollers 117 positioned between the ring 110 and plungers 118 which are movable in radial chambers 119 of the rotor. Chambers 119 serve as oil pump chambers with a conduit 120 conducting pumped oil to the upper portion of a chamber 121 in which the control plunger 122 is axially movable. The latter is splined to the shaft 123 of the rotor so as to rotate with the latter but to be axially movable in the chamber 121. The plunger is provided with a tapered groove 124 to control fuel discharge ports 125 as hereinbefore described with respect to the plunger 46. Interiorly of the plunger 122 a ball bearing 126 is arranged so as to carry, non-rotatably with the plunger, a connecting rod 127 which projects through the housing part 103 forming the cover of chamber 121. A spring 128 bears with its one end against the housing part 103 and with its other end on the bearing 126 so as to exert pressure on the valve in a direction opposite to that of the fuel-filled ring space 116. The upper end of the rod 127 is secured to the center of a diaphragm 129 spanned between the housing portions 103 and 104 so as to form a vacuum chamber 130 with a socket 131 on its top for connection to the manifold of an engine.

Now it will be clear that the embodiment of Fig. 10 operates fundamentally in the same manner as the embodiment of Fig. 1 with the difference, however, that the oil pump chambers are arranged interiorly of the rotor, whereas the fuel pumping elements are formed by the rollers guided in rotor 107 in the chamber formed by the rotor and the surrounding eccentric ring 110. The plunger 122 also is subject to forces of the same quality as those to which the plunger 46 responds inasmuch as the vacuum in chamber 130 tends to counteract the pressure of spring 128 and as the plunger 122 is subjected on the one side to the fuel and on the other side to the

oil, both under pressure caused by the respective pumps. The oil circulating passages are also provided in a manner similar to that described, as a helical groove 132 in the plunger side connecting the upper portion of chamber 121 to an axial conduit 133 which in turn is connected to the oil inlet at 140. The operation of the pump of Fig. 10 will be understood without further explanation in view of what has been stated with reference to the embodiment of Figs. 1 to 9.

In the foregoing it has been shown that the pump according to my invention is useful to deliver simultaneously two different fluids. However, it is also possible to use the described pump for the purpose of acting on only one fluid in a two-stage compression if certain modifications are provided which mainly comprise a connection between the chambers of the one pump part and the other one. A pump thus modified may be employed for instance, for charging an engine with kerosene which has certain lubricating qualities, so that no other lubricant is required for the movable parts of the pump. Fig. 11 illustrates the main portions of such a pump wherein the rotary pump part constitutes the elements of the first stage and the plunger pump part constitutes the elements of the second stage of compression. In this pump, which comprises in an arrangement similar to that described hereinbefore, a housing 201 in which the rotor 202 is rotatable between the plates 203 and 204, and interiorly of the eccentric ring 205. The pump chamber 206 of the first stage is formed between the rotor and the ring 205. To this chamber the fluid may be admitted through an opening 207 with conduit 208 when the rollers 209 pass the port 210 in the upper plate 204. From chamber 206 the fluid will be expelled through opening 211 and conduit 212 so as to enter a receiving chamber 213 in the housing. From there the fluid may enter the plunger chambers 214 through ports 215 and 216 in plate 203 and rotor 202 respectively when these ports are in registry. The fluid entering the receiver 213 is therefore compressed in the first stage and will then be further subjected to additional pressure by the plungers 217 until the ports 218 and 219 are in registry. If this occurs the fluid subjected to the second stage of compression will be forced into the annular space 220 from where it may be ejected through a port 221 controlled by the groove 222 of the control plunger 223, in a manner more or less similar to that described with respect to the pumps of Figs. 1 and 10. It will be noted that in the case of this modification no pressure fluid acts on the slide valve plunger 223 from the top. In order to compensate for such lack of pressure from above, a stronger spring 224 may be used in loading the plunger so as to counteract the pressure in the space 220 to a desired degree. Of course, safety organs may be applied to permit back flow from chamber 220 to receiver 213 and also from the receiver 213 to the inlet 208. Such organs may be of a structure and arrangement similar to the valves 54 and 70 respectively, shown in Fig. 1 with their accessories and conduits.

Having now described several embodiments of my invention, it will be apparent to those skilled in the art that many alterations and modifications of the mechanism illustrated and described are possible without departing from the spirit and essence of my invention which for this rea-

son shall be limited only by the scope of the appended claims.

I claim:

1. A combined pump for fuel and oil comprising a rotor including side walls, a housing for said rotor in eccentric relation thereto so as to form with said rotor a first pump chamber and including side walls in fluid-tight engagement with said rotor side walls respectively, a roller in engagement with said housing and guided in radial slots provided in said rotor so as to be rotatable with the latter, an inlet and an outlet port for one of said two fluids in said housing and under the control of said roller, means to cause reciprocation of said roller radially in relation to said rotor, said means including a spring-biased plunger engaging said roller and tending to urge it against said housing, said rotor being provided with a radial cylindrical chamber constituting a second pump chamber with said plunger reciprocatable therein, an inlet port and an outlet port for the other one of said fluids in the rotor side walls respectively and in communication with said second pump chamber and orifices in the side walls of said housing so arranged as to communicate with said inlet and outlet ports respectively in predetermined angular positions of said rotor in relation to said housing.
2. A combined pump for fuel and oil comprising a rotor including side walls, a housing for said rotor including an inner peripheral wall and side walls, said inner wall having a plurality of sections eccentric in relation to said rotor so as to form with the latter as many first pump chambers as there are sections, said side walls being in fluid-tight engagement with the rotor side walls respectively, a plurality of fluid-propelling elements, the number of which may differ from that of said chambers, said elements being in engagement with the inner housing wall and said rotor and rotatable with the latter so as to pass said first chambers one after the other, an inlet port and an outlet port for one of said fluids in each of said first chambers and under the control of the passing elements, a means for each of said elements to cause reciprocation thereof radially in relation to said rotor, each of said means including a spring-biased plunger engaging the associated element and tending to urge it against said inner housing wall, said rotor being provided with a plurality of radial chambers, one for each plunger and constituting second pump chambers, each of said second chambers having an inlet and an outlet port for the other one of said fluids in the rotor side walls respectively, as many inlet and outlet orifices as there are first chambers, said orifices being so arranged as to register successively with said inlet and outlet ports for said other fluid respectively in predetermined positions of the rotor during its rotation.
3. A combined fuel and oil pump comprising a rotor including therein a radially arranged first pump part including an inner wall, a housing for said rotor and including an inner wall portion, means rotatable with said rotor and in engagement with said inner wall, said means, said inner wall portion and said rotor constituting a second pump part, one of said pump parts being adapted to pump fuel, the other one to pump oil, a chamber provided in said housing in coaxial arrangement with said rotor so as to receive fuel from the fuel pump part, a slide valve in said chamber in rotatable connection with

said rotor so as to control an outlet orifice in the wall of said chamber, and ducts in the housing to conduct oil from the oil pump part to the movable members of the device.

4. A combined pump for fuel and oil comprising a rotor including therein a radially arranged first pump part, a housing for said rotor and including an inner wall portion, means rotatable with said rotor and in engagement with said inner wall portion, said means, said inner wall portion and said rotor constituting a second pump part, one of which parts being adapted to pump fuel, the other one to pump oil, a cylindrical chamber provided in said housing in coaxial arrangement with said rotor, conduits from said pumps to the opposite chamber end portions respectively, an outlet from said chamber intermediate its ends, relief valves in communication with said chamber portions respectively, a plunger valve in said chamber so as to be exposed on its opposite sides to the fuel and oil pressures prevailing in said chamber portions respectively, said plunger being rotatable with said rotor and movable in axial direction and being provided with a tapering groove in its side wall so as to control said outlet according to the rotor rotation and in response to differences of the fuel and oil pressures and to connect said outlet temporarily with the chamber portion connected to said fuel pump part.

5. A combined pump for fuel and oil comprising a rotor including therein a radially arranged first pump part, a housing for said rotor and including an inner wall portion, means rotatable with said rotor and in engagement with said inner wall portion, said means, said inner wall portion and said rotor constituting a second pump part, one of said parts being adapted to pump fuel, the other one to pump oil, a cylindrical chamber provided in said housing in coaxial arrangement with said rotor, conduits from said pumps to the opposite chamber end portions respectively, and outlet from said chamber intermediate its ends, a first relief valve in communication with the chamber portion connected to the fuel pump part, a second and a third relief valve in communication with the chamber portion connected to the oil pump part, said second relief valve opening towards an inlet to the oil pump part, said third relief valve being adjusted to open towards the outside under a higher pressure than said second relief valve, a plunger valve in said chamber so as to be exposed on its opposite sides to the fuel and oil pressures prevailing in said chamber portions respectively, said plunger being rotatable with said rotor and mov-

able in axial direction and being provided with a tapering groove in its side wall so as to control said outlet according to the rotor rotation and in response to differences of the fuel and oil pressures and to connect said outlet temporarily with the chamber portion connected to said fuel pump part.

5 6. A pump as claimed in claim 5, said plunger being provided with a substantially helical lubricating groove in its side wall, and said groove constituting a portion of the connection between said second and third relief valves and the chamber portion connected to said oil pump.

7. A combined fuel and oil pump comprising 15 two parts, one adapted to pump fuel, the other one to pump oil, a substantially cylindrical housing with a plurality of ports in its side wall, a slide valve rotatable and axially shiftable in said housing and dividing the latter in a first and a second chamber, said valve being a means to connect one of said ports after the other to said first chamber and to meter the flow through said ports according to its axial position, resilient means 20 in engagement with said housing and said valve so as to bias the latter in one axial direction, a first conduit from the pressure side of said fuel pump part to said first chamber, and a second conduit from the pressure side of the oil pump part to said second chamber.

8. A combined fuel and oil pump comprising 25 two parts, one adapted to pump fuel, the other one to pump oil, and including a rotatable shafted pumping member, a substantially cylindrical housing coaxial with said member and having a plurality of ports in its side wall, a slide valve 30 in said housing and connected for common rotation with said member but being axially shiftable, said valve being a means to connect one of said ports after the other to said first chamber and to meter the flow through said ports according to its axial position, resilient means in 35 engagement with said housing and said valve so as to bias the latter in one axial direction, a first conduit from the pressure side of said fuel pump part to said first chamber, a second conduit from the pressure side of the oil pump part to said second chamber, an axial discharge conduit in 40 said member including its shaft, and a duct in said valve connecting said second chamber to said discharge conduit.

45 9. A pump as claimed in claim 8 further comprising branch conduits of said discharge conduit to the movable parts of the pump to lubricate the latter.
